SIGN

Ramsay G. Regester, Philadelphia, Pa., assignor
to Gill Glass & Fixture Company, Philadelphia, Pa., a corporation of Delaware

Application August 18, 1938, Serial No. 225,511

3 Claims. (Cl. 40—130)

The present invention relates to signs, and is more particularly directed toward edge lighted signs adapted to employ a replica of the article being advertised as a lamp housing.

- 5 5 A further object of the present invention is to provide an edge lighted sign with a peripheral band of colored pigment adapted to be illuminated when the sign is lighted and to simulate the appearance of a neon tube.
- 10 10 The accompanying drawing shows, for purposes of illustrating the present invention, one embodiment in which the invention may take form, it being understood that the drawing is illustrative of the invention rather than limiting 15 15 the same.

In the drawing:

Figure 1 is a side elevational view of the sign with parts in section; and

Figure 2 is a horizontal sectional view taken 20 20 on the line 2—2 of Figure 1.

In the drawing a sign is shown as having a generally cylindrical base 10 provided with a lateral extension 11 and apertured as at 12 to accommodate the wires. The base supports a 25 25 lamp socket 13 which carries a lamp bulb 14. The socket and bulb are surrounded by a lamp housing 15 which conveniently takes the form of a container for goods to be advertised, for example, a bottle such as shown. This lamp housing is hollow and has a slot in the wall as indicated at 16.

A sign plate 17 provided with suitable sign indicia extends into the slot 16, so as to be near the lamp bulb, and the bottom of the sign plate 30 30 rests on the extension 11, preferably in the slot 18 as indicated. The sign may have any desired contour.

In the simple form shown all the exposed edges of the sign plate are beveled, as indicated at 19, 35 35 and provided with a pigment indicated by the stippling. This pigment picks up the light rays in the glass and reflects them out through the front face providing a colored band which simulates the appearance of a neon tube.

In the form of construction shown the lamp housing 15 is independent of the base and upwardly removable to permit access to the lamp bulb and socket. It will, of course, be obvious that these two parts may be made integral and the lamp and socket mounted in this integral member in a suitable manner. Other forms of container may be used, such as a milk bottle, milk can, beer keg, etc.

It is obvious that the invention may be embodied in many forms and constructions within the scope of the claims and I wish it to be understood that the particular form shown is but one of the many forms. Various modifications and changes being possible, I do not otherwise 15 15 limit myself in any way with respect thereto.

What is claimed is:

1. A sign comprising a base, a lamp socket and lamp bulb carried by the base, an opaque lamp receptacle above the base and having a 20 20 slotted wall, an extension on the base below the slot, and an edge lighted indicia carrying plate extending into the slot and supported on the extension, the edge of the plate being beveled on the back side and coated with a colored pigment so as to present a colored peripheral band.

2. A sign adapted to advertise a beverage comprising a base, a hollow replica of a container carried by the base, a lamp disposed in the replica, the replica having a vertical slot in its side 30 30 wall, an extension of the base below the slot, the extension having a slot, and an edge lighted indicia carrying plate extending into the first slot to receive light from the lamp and into the second slot to be supported therein.

3. An edge lighted sign comprising a lamp housing, an indicia carrying plate having an edge adjacent the lamp to admit light and exposed edge portions provided with pigment carrying beveled areas whereby an illuminated colored band is provided about the exposed edges of the sign.

RAMSAY G. REGESTER.
